CLAIM

The ornamental design for an irrigation controller with reversible operator controls, as shown and described.

DESCRIPTION

FIG. 1 is a front perspective view of an irrigation controller with reversible operator controls showing my new design.

FIG. 2 is a rear perspective view thereof.

FIG. 3 is a front elevational view thereof.

FIG. 4 is a rear elevational view thereof.

FIG. 5 is a left-side elevational view thereof.

FIG. 6 is a right-side elevational view thereof.

FIG. 7 is a top plan view thereof; and,

FIG. 8 is a bottom plan view thereof.

The broken lines shown are included for the purpose of illustrating portions of the irrigation controller with reversible operator controls that form no part of the claim.

1 Claim, 6 Drawing Sheets

Related U.S. Application Data

continuation of application No. 16/395,884, filed on Apr. 26, 2019, now Pat. No. 10,561,079, which is a continuation of application No. 15/267,893, filed on Sep. 16, 2016, now Pat. No. 10,285,344.
